Primary Examiner — Janice Hallmark*Assistant Examiner* — Emily Anna Saunders(74) *Attorney, Agent, or Firm* — Andrew C. Cheng(57) **CLAIM**

I claim the ornamental design for a toy egg, as shown and described.

DESCRIPTION

FIG. 1 is a first perspective view of a toy egg showing my new design;

FIG. 2 is a second perspective view of the toy egg of FIG. 1, viewed from another aspect;

FIG. 3 is a front view of the toy egg showing my new design;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the toy egg in which the design is embodied that form no part of the claimed design.

1 Claim, 8 Drawing Sheets(56)
